United States Patent Office

Des. 187,080
Patented Jan. 19, 1960

187,080

LACE FABRIC

Lawrence Malkin, New York, N.Y., assignor to D. Strauss
Co., Inc., New York, N.Y., a corporation of New York

Application September 11, 1959, Serial No. 57,514

Term of patent 7 years

(Cl. D47—6)

The figure is a plan view of a lace fabric, showing my new design.

I claim:

The ornamental design for a lace fabric, substantially as shown.
